UNITED STATES PATENT OFFICE.

JOHN KRATZ, OF BALTIMORE, MARYLAND.

CABLE-GRIP.

SPECIFICATION forming part of Letters Patent No. 498,517, dated May 30, 1893.

Application filed April 3, 1893. Serial No. 468,777. (No model.)

To all whom it may concern:

Be it known that I, JOHN KRATZ, of the city of Baltimore and State of Maryland, have invented certain Improvements in Gripping Devices for Cable Railways, of which the following is a specification.

This invention relates specifically to certain improvements in the lower or movable grip shoe, which, to place the car in motion, is drawn upward so as to clamp or grip the cable between itself and the fixed grip shoe; and the object of the invention is to prevent the cable, when the car is stopped, from bearing on the gripping portion of the lower or movable shoe, as will hereinafter fully appear.

In the further description of the said invention which follows, reference is made to the accompanying drawings forming a part hereof in which—

20 Figure 1 is an end view of the lower part of the cable grip; and Fig. 2 a section of Fig. 1 taken on the dotted line $x-x$, showing the positions of the various parts thereof when the cable is released. Fig. 3 is a view similar to Fig. 2 except that the cable is shown as gripped. Fig. 4 is a top view of the lower grip shoe alone, and Fig. 5 an under side view of the same.

Referring to the drawings, A represents the 30 stationary section, and B the movable section of the grip frame.

C is the upper or stationary grip shoe, which is of ordinary construction.

D is the lower and movable grip shoe composed principally of the central part *a* and the end pieces *b* and *c*. The end pieces *b* and *c* are pivoted or hinged to the central part *a* in any appropriate manner.

E, *E* are grooved rollers, adapted to turn in 40 oil pockets *f* in the end pieces *b* and *c* of the grip shoe. F is a spring secured to the central part *a* of the shoe with its ends bearing

against the under face of the end pieces *b* and *c*. The strength of the spring is such that when the shoe is lowered it forces the end pieces *b* and *c* up, and the rollers then support the cable from contact with the central portion *a* of the shoe. When the shoe is lifted to apply the grip, the central part *a* only of the shoe is raised, and the rollers *E* *E* 45 and the end pieces *b* and *c* become inoperative. By this construction, the cable when not used to propel the car is supported from the surface of the central part of the shoe and there is considerably less wear on the cable than 55 when it is dragged over a resisting surface. The rollers being partially immersed in oil, the wear on their bearings is much reduced.

I claim as my invention—

1. In a gripping device for a cable car, the 60 combination of a stationary grip shoe, a vertically moving lower shoe which consists of a center piece, with spring supported end pieces hinged to the center piece and extending longitudinally of the same, and rollers journaled in the said end pieces, whereby as the said center piece is lowered the cable is supported by the said rollers and out of contact with the center piece, substantially as and for the purpose specified. 70

2. In a gripping device for a cable car, the lower grip shoe having spring supported hinged end pieces provided with rollers situated in oil boxes, substantially as specified.

3. In a gripping device for a cable car, a 75 lower grip shoe having spring supported end pieces which extend longitudinally thereof, combined with rollers journaled in the said end pieces, substantially as specified.

JOHN KRATZ.
